UNITED STATES PATENT OFFICE

WALTER H. BERNADT, OF BUFFALO, NEW YORK

CONVEYER CONTROL

Application filed December 27, 1929. Serial No. 416,806.

This invention relates to an automatic mechanism for stopping a conveyer when the accumulation of the material being discharged therefrom has reached a predetermined level. It proposes a control which is especially designed for but not necessarily limited to coke handling operations.

In the handling of coke during crushing and grading operations, it is the practice to transfer the coke to and from crushing and grading apparatus upon a succession of belt conveyers and in some instances it is discharged from one conveyer directly onto another. It sometimes happens that the path of travel of the coke from its starting point to the point where it is discharged for final disposal is broken as a result of the stopping or slowing up in speed of one of the conveyers or the choking of the crushers or grizzlies. When this occurs, unless the conveyers which are delivering the coke to the disabled mechanism are stopped, an accumulation of the coke develops which increases to a point where its overflow occurs. This requires an interruption in the operation of the entire line of conveyers, crushers and graders until the material has been cleared away by hand shoveling, the time required to do this depending upon the elapsed time between the breakdown of the conveyer or other mechanism and the stopping of the line of feed conveyers.

The principal object of the present invention is to provide a device to be used in conjunction with conveyers, crushers, grizzlies and other mechanisms which will become effective immediately, upon the accumulation of material in the path of travel beyond a predetermined height, to stop the conveyer or conveyers which are feeding the material to that point where the excessive accumulation has commenced.

The device is designed to stop the feed conveyers before the accumulation referred to has reached a point where overflow occurs and as a result therefore, no hand shoveling, with the resultant loss of time, is necessary and immediately upon the repair of the defective mechanism the entire line of mechanisms may be started at once.

The invention is illustrated in the accompanying drawings in which:—

Figure 1 is a vertical section of a grizzly and feeding mechanism therefor showing one application of my invention. 55

Figure 2 is an end elevation of the same.

Figure 3 shows the control mechanism in conjunction with a hopper which is arranged to facilitate the transfer of the material from one conveyer to another. 60

While the invention is described in connection with treating and conveying of coke it is to be understood that such description is merely for purposes of illustration and that in fact the invention is available for other mechanisms and purposes so long as the electrical conductivity of the material being acted upon is suitable for the purposes in view. 65

The control mechanism is illustrated in Figures 1 and 2 in connection with a grizzly 4 and a feed conveyer 5 therefor, only the essential parts of the apparatus being shown for purposes of clarity. The feed conveyer 5 may be driven by an electric motor 5a. The grizzly 4 includes spaced bars 6 which provide screening openings 7. The coke or other material is discharged from the feed conveyer 5 onto the grizzly 4 down which it rolls to a chute 8 from whence it may be carried away in any suitable manner. In the passage of the material from the feed conveyer to the discharge chute 8, however, the smaller particles are separated therefrom by the grizzly 4, the finer particles of the material passing through the openings 7 and dropping upon a conveyer 9 which is positioned beneath the grizzly and which is adapted to convey them to a different point of discharge. The construction described to this point is representative of apparatus for grading coke and is standard equipment. 80 85

In the grading of the coke it may happen that the screening openings in the grid become choked or one of the conveyers 8 and 9 breaks down or slows up appreciably. Upon such an occurrence if the conveyer 5 continues to deliver its usual flow of material, the material accumulates and rapidly reaches a point where it overflows its path. 90 95 100

This requires its subsequent handling by hand and also chokes up parts of the apparatus. The amount of material accumulating in the path of flow and overflowing the same depends, of course, upon the time that the feeding conveyers continue in operation after a mechanism in the path of flow has become disabled.

In order to avoid such occurrences, I propose to employ a switch mechanism which is controlled by contact members positioned adjacent the path of flow of the material being acted upon and in such relation therewith that if for any reason the material accumulates in the path beyond a certain height a circuit is closed to operate the switch mechanism and break the circuit through the motor which is driving the conveyer or other mechanism feeding that portion of the apparatus where the accumulation has commenced.

The switch and automatic operating mechanism therefor which are indicated as a whole at C (Fig. 1) may be positioned wherever desired but are preferably located in the switch box containing the switches employed in connection with the other motors of the apparatus.

Means for starting the automatic switch operation mechanism is, as stated, positioned adjacent the path of flow of the material being acted upon at any number of points desired. As illustrated in Figures 1 and 2 each of said means comprises pairs of depending contact arms 10 which are pivotally supported at their upper ends between brackets 11 secured to cross members 12. The cross members 12 may be supported by the side walls of the grizzly at such a distance from the bottom thereof that the contact arms are held above the screening surface of the grizzly at such a height that in the normal operation of the apparatus the material passes beneath the said arms without touching them. The cross members 12 are, of course, insulated from the depending arms 10 and their supporting brackets.

As illustrated in Figure 1, the feed conveyer may be started by closing a circuit through the motor 5a. The circuit is closed by operating the hand switch 13 of the control mechanism C. A circuit is thereupon established through the A side of the power line, contacts 14 and 15, which are normally held closed by the spring 16a, switch 13, solenoid 16 and out the B side of the power line. The solenoid 16, upon being energized closes the switch 17 and the motor circuit is closed. The closing of the switch 17, however, also closes a circuit by means of wires 18 and 19 through the primary winding of a transformer 20. The secondary winding of the transformer forms part of a normally open circuit which includes wire 21 grounded to the frame of the grizzly as at 22 and wire 23 which is connected to electric magnets 24. The circuit

through wire 23 and magnets 24 continues through wires 25 to the binding posts 26 which are electrically connected through the brackets 11 to the arms 10.

It will thus be obvious that during the normal operation of the apparatus the secondary circuit will be open and the spring 16a will hold the contacts 14 and 15 closed to maintain the energization of the motor 5a. However, should the coke or other conductive material which is being treated back up against any one of the fingers 10, a closed circuit is established from that finger through the coke which has backed up beneath it, the frame of the grizzly, wire 21, magnets 24, wire 25 and the electric magnets 24 are thereby energized to attract the armature 27 which opens the contacts 14 and 15 to break the motor circuit and stop the feed conveyer 5. Upon the clearing away of the material beneath the arms 10, the secondary circuit will be broken and a circuit will again be closed through the motor 5a. It will thus be apparent that by utilizing the invention in the manner described a feed conveyer will be automatically stopped when the material beyond the discharge end thereof has reached a predetermined level and that any overflow of the material may, therefore, be effectually prevented.

In Figure 3 the invention is illustrated in connection with two conveyers with a hopper arranged between the two and adapted to facilitate the transfer of the material from one of the conveyers to the other. The feed conveyer 28 which is driven by motor 29 delivers the material into the hopper 30. The discharge mouth 31 of the hopper is arranged to deliver the material received from the feed conveyer 28 to a second conveyer 32 which is driven by the motor 33.

In connection with this modification of the invention it is to be noted that in grading and crushing coke, it is the practice to utilize such an arrangement of conveyers to receive the finer particles of coke from the grizzly and carry them to the ultimate point of discharge. In such an arrangement the hopper 30 would be positioned beneath the upper end of the conveyer 9 (illustrated in Figure 1). In other words the said conveyer 9 would be utilized to feed material to the hopper 30 instead of the conveyer 28 shown in Figure 3. In any event it is preferred that the motors for driving the various conveyers be adapted for independent starting, that is to say, have independent switches which permit them to be started preferably in sequence from the end of the line toward the beginning of the line. In such a construction the automatic control mechanisms are preferably arranged so as not only to stop the conveyer feeding directly to the point where the accumulation has commenced but also all of the conveyers in the line which precede it, the conveyers

beyond the point of accumulation continuing in operation to clear that portion of the apparatus.

To this end, therefore, the motor 33 (Figure 3) is started first by closing the switch 36. After the switch 36 has been closed, the switch 18 may be operated to energize the solenoid 16 and close switch 17. In other respects the control mechanism and wiring 10 therefore is substantially the same as illustrated in connection with Figure 1 and the same reference characters are therefore employed.

However, in place of the contact arms 10 utilized in the first embodiment illustrated, I propose to employ contact fingers 34 which are preferably suspended by a support 35 from the inner wall of the hopper and over the discharge mouth of the same, the fingers 34 being insulated from the support 35 as at 35a. The secondary circuit of the transformer 20 includes wire 21 which may be grounded to the hopper 30, magnets 24 for operating the armature 27 and wire 25 connected to the fingers 34. If for any reason the conveyer 32 should stop or slacken its normal speed and the coke back up in the hopper to such a height as to contact with the fingers 34 the secondary circuit will be 20 closed, utilizing the coke and hopper as part of the circuit, to break the circuit through the motor 28 as described in the first embodiment of the invention. While the circuit through motor 28 is broken the circuit 30 through motor 33 will, of course, not be effected and the conveyer 32 will continue in operation.

In both embodiments of the invention the relation between the primary and secondary 40 windings of the transformers is preferably such that the voltage in the secondary circuits is not high enough to be dangerous to workmen. However, the current, voltage and frequency may be varied in order to meet different conditions such as, for example, materials offering different resistances to the passage of current.

Having described my invention I claim:—

1. In apparatus for transferring electrically conductive material from one point to another, a conveyer for delivering the material to a point of discharge, a motor operatively connected to said conveyer, a normally closed circuit through the motor, means arranged to provide a path of flow for the material discharged from said conveyer, contact means arranged adjacent the said means and electrically controlled means operable to break the circuit through said motor when the material in the path of flow has reached a height sufficient to contact with said contact means, the said material providing a conductor between said contact means and said electrically controlled means.

2. In apparatus for transferring elec-

trically conductive material from one point to another, a conveyer for delivering the material to a point of discharge, a motor operatively connected to said conveyer, a normally closed circuit through the motor, 70 means arranged to provide a path of flow for the material discharged from said conveyer a contact member pivotally mounted adjacent said means and electrically controlled means operable to break the circuit 75 through said motor when the material in the path of flow has reached a height sufficient to contact with said contact member, the said material providing a conductor between said contact member and said electrically 80 controlled means.

3. In apparatus for transferring material from one point to another, a conveyer for delivering the material to a point of discharge, a motor operatively connected to said 85 conveyer, a normally closed circuit through said motor, means arranged to provide a path of flow for the material discharged from said conveyer, automatic means for breaking the circuit through said motor said 90 means including a transformer having its primary winding in the motor circuit, the secondary winding of said transformer being included in a normally open secondary circuit and means adjacent the path of flow 95 and adapted when the material in the path of flow has reached a predetermined height to close said secondary circuit.

4. In apparatus for transferring material from one point to another, a conveyer for 100 delivering the material to a point of discharge, a motor operatively connected to said conveyer, a normally closed circuit through said motor, means arranged to provide a path of flow for the material discharged from said conveyer, automatic 105 means for breaking the circuit through said motor comprising a transformer having its primary winding in the motor circuit, the secondary winding of said transformer being included in a normally open secondary circuit and means adjacent the path of flow 110 and adapted when the material in the path of flow has reached a predetermined height to close the secondary circuit and effect the 115 operation of said automatic means, said material constituting a part of the said secondary circuit.

5. In apparatus for transferring electrically conductive materials from one point to another, a conveyer for delivering the materials to a point of discharge, a motor operatively connected to said conveyer, a normally closed circuit through said motor and automatic means for breaking the circuit 120 through said motor comprising a transformer having its primary winding in the motor circuit, a normally open secondary circuit including the secondary winding of said transformer, an electric magnet in said secondary 125 130

circuit, means in said circuit arranged adjacent the path of flow of the materials and adapted when the materials therein have reached a predetermined height to cooperate

6 with said materials to close said secondary circuit, thereby to operate said magnet and break said motor circuit.

10 6. In apparatus for transferring electrically conductive materials from one point to another, a conveyer for delivering the materials to a point of discharge, a motor operatively connected to said conveyer, a normally closed circuit through said motor, a second conveyer for carrying off the materials discharged from the first mentioned conveyer, means arranged between the two conveyers for facilitating the transfer of the materials, contact means carried by said means, and electrically controlled means operable to

15 break the motor circuit when the materials being transferred back up beyond their normal height to contact with said contact means, the said materials providing a conductor between said contact means and said electrically controlled means.

20 7. In apparatus for transferring electrically conductive materials from one point to another, a conveyer for delivering the materials to a point of discharge, a motor operatively connected to said conveyer, a normally closed circuit through said motor, a second conveyer for carrying off the materials discharged from said first mentioned conveyer, intermediate means arranged between

25 the two conveyers for facilitating the transfer of the materials from one to the other, automatic means for breaking the circuit through said motor comprising an armature carrying a contact, a magnet for operating

30 said armature, said magnet being included in a normally open circuit and contact means as a part of said circuit carried by said intermediate means and adapted to contact

35 with the materials being conveyed should the materials back up in the intermediate means beyond a predetermined height, said materials being utilized in such case as a conductor to close the normally open circuit through said magnet.

40 50 In testimony whereof I affix my signature.
WALTER H. BERNADT.
